UNITED STATES PATENT OFFICE.

JOSEPH LEVINE, OF BROOKLYN, NEW YORK.

RECORDING BOOK BANK.

Application filed May 15, 1923, Serial No. 639,048. Renewed March 7, 1925.

To all whom it may concern:

Be it known that I, JOSEPH LEVINE, a citizen of the United States, residing at Brooklyn, in the county of Kings and State of New York, have invented certain new and useful Improvements in Recording Book Banks, of which the following is a specification.

This invention relates to recording book banks, and the main object is to provide a bank in which coins of various denominations may be stored and the amount in the bank may at any time be readily observed.

Another object is to provide a bank as mentioned having the appearance of a book, and a novel type of lock which engages the entire length of the opening side, and which, when locked, cannot be pried open.

These and other objects will become apparent in the description below, in which characters of reference refer to like-named parts in the drawing.

Referring briefly to the drawing, Figure 1 is a side elevational view of the device, 25 showing the coin receiver side.

Figure 2 is a sectional elevational view of the same, taken on line 2—2 of Figure 1.

Figure 3 is a sectional plan view taken on line 3—3 of Figure 1.

30 Figure 4 is an enlarged sectional elevational view taken on line 4—4 of Figure 3, showing the locking means in the secured position.

Figure 5 is a similar view showing the lock in released position.

Figure 6 is a sectional elevational view taken on line 6—6 of Figure 4.

Referring to the drawing in detail, the numeral 10 indicates the rear side wall of the device rigidly fixed to a substantially U-shaped frame 11. One of the longitudinal edges is bent angularly and curvedly, and provides the lower wall or back 12. The front side of the frame 11 is covered by a 45 rectangular door 13 fashioned after a book cover and having extending slip hinges 14 on its lower edge. Said hinges are inserted beneath an angular projecting plate 15 forming part of the back 12. Both the door 13 and rear side 10 are provided with border frames 16 which enclose the corners and have numerals 17 graduated thereon, said numerals being indicative of the denominations of coins. A plurality of slots 18 are 50 formed near the upper edge of the door, the

largest of said slots being horizontal, the remainder being slightly inclined. Said slots provide openings through which coins are passed into the bank. Beneath the slots a plurality of vertically spaced-apart 60 holes 19 are formed and lines which are graduated on the surface of the cover, have numerals which indicate the monetary value of the coins in the slots.

A platform 20 having a turned-down 65 reinforcing edge supports a plurality of cylinders 22 slotted lengthwise, the slotted portions facing and lying adjacent the door 13. A relatively long hinge pin 23 is mounted on the inner face of the door 13 70 and has a plate 24 connected thereto covering the upper end of the cylinders 22. Spring elements 25 having a pair of resilient arms, are supported on the hinge pin 23, one arm being adapted to cover the central 75 portion of its respective slot 18, the other contacting with a flange 26 fixed to the inner surface of the door. The cover 24 has a plurality of upwardly extending ears 27 projecting from its surface near the hinged 80 end, said ears being engaged by a locking lip 28. The latter extends angularly from a bar 29, said bar being of substantially U-shaped conformation. The side opposite to the lip, indicated by the numeral 30, is 85 bent downwardly, and is supported by curved lip extensions 31. An arm 32 extends from one of the short edges of the bar 29, and has an upturned ear 33 formed at its lower end.

90 The means for actuating the bar 29 is located on the inside of the casing and comprises a plate 34 slidable between a fixed body plate 35 and the surface of the bar 29, said plate 34 having ridges 36 formed on its 95 opposite sides engaging the side edges of the fixed plate 35 and providing guides for slide plate 34. A pair of substantially rectangular extensions 37 project from one side of the slide plate 34, and when the bar 29 is 100 in locked position, the ear 33 will slip between said extensions 37. An opening 38 is formed in the plate 35 and is provided as a centering means for a key 39 which may be inserted through the side of the casing from 105 without. Said key is preferably of the flat type and has dogs 40 thereon, the larger one of which is inserted into a rectangular orifice 41 formed in the arm 32 and an arcuate orifice 42 formed in the slide plate 34. The 110

latter is normally urged toward one side of the device by a spring 43, one end of which is fixed to an ear 44 of the slide plate, and its other end is secured to a similar ear 45, the latter being rigid with the frame 11.

This bank is used in a manner similar to those now on the market, and has for its purpose the storage of coins which may not be removed except by authorized persons.

10 The coins are slipped through the slots 18. As the coin is inserted, the spring arm 25 will be urged aside by the coin and the latter will fall to the bottom of its respective cylinder 22. As the coin leaves the region of the slot, the rear resilient arm of the spring 25 will urge the forward arm across the slot. When the spring is in this position and the bank is inverted, it will be impossible for the coins to be removed thru the slots as said spring arm 25 covers the same. When the coins are to be removed from the cylinders, the door 13 is opened and the cover 24 is then rotated about its hinge pin 23 until the entire block of cylinders 20 may be lifted from the surface of the door, after which the coins may be conveniently removed.

The means for locking the door 13 in the closed position, indicated in Figures 2 and 30 4, comprises a locking bar 29 extending the entire length of the device and pivoted at its rear end. As the key is inserted into the hole in the side of the frame, the dog 40 thereon will engage the side edges of the orifices 41 and 42. As the key is rotated, the slide plate 34 and the arm 32 are simultaneously actuated. The arm 32, being rotated about the ear 31 and the slide plate 34, is lifted upward against the tension of spring 43. The ear 33 at the lower end of the arm 32, during this interval, will move in an arcuate path and finally come to a position of rest between the extensions 37 of the slide plate 34. When in this position, the locking 40 45 bar 29 is lifted as shown in Figure 5, and the door 13 may be readily opened. In locking the door, the key is rotated in an opposite direction, thereby shifting the locking elements into the position shown in Figure 4.

It is to be noted from Figure 1, that the surface of the door outside of the border frame 16 is covered with material such as leather. It is obvious that certain changes 55 in construction, such as finishing the surface of the casing completely with leather or other material may be made, without departing from the spirit or scope of the invention.

60 I claim:—

1. A recording book bank comprising a rectangular casing, one side of said casing being open, a removable door covering said opening and having slots therein, a hinge pin mounted on said door, spring arms on

said hinge pin normally covering said slots, a platform on said door, coin-receiving cylinders on said platform, a cover plate pivoted on said hinge pin and adapted to cover the cylinders, a locking bar in said casing, 70 and means on said cover plate for engaging the locking bar.

2. A recording book bank comprising a rectangular casing, one side of said casing being open, a door covering said casing and 75 having a plurality of slots therein, a platform mounted on the door, a row of cylinders mounted on said platform, a hinge pin on said door above the cylinders, a plate pivoted on said pin covering said cylinders, ears 80 on said cover plate, a locking bar pivoted in said casing engaging the ears when in locked position, a plurality of resilient arms normally covering the slots in the cover, means engaging the sliding bar for releasing the 85 door, and means for securing the sliding bar in the locked or unlocked position.

3. A recording book bank comprising a rectangular casing, a door covering one side of said casing and having a plurality of coin receiving slots therein, a platform mounted on the door, a row of cylinders on said platform aligned with the coin receiving slots, a hinge pin in said door above said cylinders, 90 a plate pivoted on said pin covering said cylinders, upright ears on said cover plate, a pivoted locking bar in said casing, an angular lip on said bar, said lip engaging the ears of the cover plate securing the door in locked position, and means for rotating 95 said locking bar to the released position.

4. A recording book bank comprising a rectangular casing, a door hingedly covering one side of said casing and having a plurality of coin receiving slots therein, a platform, a 105 row of cylinders mounted on said platform, said platform being removably secured to the inner surface of the door, a hinge pin on said door above the cylinders, a plate pivoted on said pin covering said cylinders and having a plurality of upright ears thereon, a bar pivoted in said casing having an angular locking lip thereon, said locking lip being adapted to engage the ears of said cover plate, an angular arm at one end of the locking bar, an upturned ear on said arm, 110 said arm having an orifice therein which is adapted to receive a key, said key when rotated adapted to move said arm, and means engaging the upturned ear for securing the locking bar arm in open position.

5. A recording book bank comprising a casing having a door thereon, a row of cylinders, a cover plate pivoted to said hinge pin and having a plurality of upright ears thereon, a bar mounted in said casing, an angular locking lip extending from said bar and adapted to engage the ears on the cover plate, an angular arm at one end of said bar having an upturned ear at its lower end, 120 125 130

said arm having an orifice therein, a fixed plate in said casing adjacent the arm, a plate slidable between the fixed plate and said arm, said slide plate having an orifice therein, a pair of spaced apart extensions on said slide plate adapted to receive the upturned ear of said arm therebetween when

the locking lip is in lifted position, and a key adapted to rotate said arm and lift said slide plate. ¹⁰

In testimony whereof I affix my signature.

JOSEPH LEVINE.
